METHOD AND APPARATUS FOR PRODUCING HELICAL GEARS

Ernest Wildhaber, Brighton, N.Y.

Application November 27, 1953, Serial No. 394,645

25 Claims. (Cl. 51—52)

The present invention relates to the production of helical teeth and more particularly to the production of helical teeth on gears which are to run either on parallel or non-parallel axes, and to the production of helical threads on worms and screws, especially helical threads of substantial lead angle. In a more specific aspect, the invention relates to the production of helical teeth and threads with rotary tools having formed cutting profiles, either milling cutters or grinding wheels. Still more specifically, the invention relates to the production of helical teeth and threads with milling cutters or with grinding wheels that have concavely curved side profiles and which produce convex tooth profiles on the work.

Because a grind wheel is a cutter with an infinite number of cutting edges, and because the invention is especially useful in grinding, we shall describe it hereafter in reference to its particular application of grinding helical gear teeth, but it is to be understood that this is intended in no way to limit the scope of the claims.

In a form-grinding operation the profile shape of the grinding wheel depends on the profile shape of the teeth or threads to be produced, but with helical teeth or threads the profile shape of the wheel is not a direct counterpart of the profile shape of the teeth or threads to be produced. This is because the contact between a grinding wheel and the helical teeth it grinds extends obliquely across the grinding surface and is not contained in a plane normal to the teeth and containing the axis of the grinding wheel. For this reason the wheel profile in that plane is less curved than the tooth profile. The wheel profile depends also on the diameter of the grinding wheel. The larger the wheel diameter the larger becomes the curvature radius of the wheel profile at a given mean point. For very large wheels, the wheel profile approaches a straight line, when the wheel is intended to grind involute helical teeth, which are the usual helical teeth.

The dependence of the wheel profile on the wheel diameter is one of the difficulties of grinding helical gears or threads with a formed wheel. Another difficulty lies in dressing the wheel to the desired shape.

These difficulties with grinding helical gears or threads are magnified where an attempt is made to grind opposite sides of the teeth simultaneously. The customary practice is to adjust the grinding wheel to the helix angle at the pitch circle; but then one side of the wheel is apt to run out of grinding contact before the other, at the ends of the tooth spaces. This occurs especially where the teeth have long or lengthened addenda, which is often the case with pinions; and it occurs even with teeth of standard addenda. When grinding continues on one side and ceases on the other side, the grinding pressure becomes unbalanced so that the grinding wheel tends to spring away from the surface still being ground and to leave more stock on the back end of the tooth. This little extra stock may result in gear noise and reduced gear life.

2

With previous methods of producing helical gears and threads, moreover, it has not been practical to produce the localization of tooth bearing or ease-off at the ends of the teeth that is desirable to render the teeth less sensitive to displacements and deflections under load, and less sensitive to manufacturing inaccuracies and tolerances.

With ease-off of the tooth surfaces at the tooth ends, the tooth contact does not sweep the entire working surface of the teeth in any given mounting position under a light load, but only a portion thereof. The tooth bearing is localized and is confined to a restricted area. The desired form of this bearing area is bounded by something like an ellipse or oval, whose major axis extends in the direction of the teeth. No grinding method has heretofore been known which can actually achieve this form of tooth bearing on helical teeth of cylindrical gears. Nor is there any cutting method known to achieve this shape on helical teeth with a formed disk milling cutter.

One object of the present invention is to provide a process in which both sides of a tooth space can be cut or ground simultaneously while maintaining the opposite cutting or grinding pressures in balance during cutting or grinding of the full length of opposite sides of a tooth space of the work.

A further object of the invention is to provide a method of cutting or grinding helical teeth in which both sides of a tooth space are cut or ground together and in which cutting or grinding contact ceases nearly simultaneously on the two tooth sides.

Another object of the present invention is to provide a method and means for producing localized tooth bearing or ease-off on helical gear teeth, and broadly to control the shape of the tooth bearing area.

Another object of the invention is to provide a method and means for cutting or grinding helical teeth in which localization of tooth bearing or ease-off at the tooth ends can be attained and controlled both as to amount and as to shape.

Other objects of the invention will be apparent hereinafter from the specification and from the recital of the appended claims.

In the drawings:

Fig. 1 is a side elevation of a helical gear, illustrating diagrammatically the conventional procedure in grinding a helical gear with a formed wheel, and showing the two zones of grinding engagement of the wheel with opposite sides of a tooth space of the gear;

Fig. 2 is a side elevation of a helical gear, but illustrating one embodiment of the present invention and showing how the two zones of grinding engagement of the wheel with opposite sides of the tooth space are aligned with each other axially;

Fig. 3 is a fragmentary view taken perpendicular to the axis of the gear and further illustrating the process of the present invention, the gear being shown in section and the grinding wheel being shown partly in section and partly in elevation;

Fig. 4 is a fragmentary normal section through the wheel and tooth space being ground in Fig. 3;

Fig. 5 is a side elevation of a helical tooth, and illustrating the form of ease-off or localization of tooth bearing desired lengthwise of the tooth;

Fig. 6 is a view similar to Fig. 5 showing the desired shape of the localized tooth bearing obtained through ease-off lengthwise and profilewise on a tooth;

Fig. 7 is a fragmentary normal section through the tooth space of a helical gear, illustrating a somewhat modified procedure;

Figs. 8 to 11 inclusive are diagrammatic views repre-

senting a portion of the gear circumference developed into a plane, together with the outline of a grinding wheel in said plane, and illustrating with exaggeration the principles of controlled tooth ease-off in accordance with the present invention, Fig. 8 showing the central position lengthwise of a tooth space and showing the grinding wheel contacting both sides of the tooth space in this central position, Fig. 9 illustrating the grinding wheel position near the tooth end with one side in grinding contact, Fig. 10 being similar to Fig. 9 but showing contact of the grinding wheel on the opposite side of the tooth space at this same tooth space end, and Fig. 11 showing the grinding wheel position near the tooth end with both sides of the wheel in grinding contact;

Fig. 12 is a fragmentary view taken at right angles to the direction of the teeth showing exaggeratedly the position of the grinding wheel adjacent the tooth end;

Fig. 13 is a diagram further explanatory of the way of obtaining a desired form of tooth ease-off in accordance with the present invention;

Fig. 14 is a fragmentary, transverse section through a grinding wheel head built to practice the present invention, the section being taken at right angles to the axis of the grinding wheel;

Fig. 15 is an axial section through the grinding wheel and its mounting;

Fig. 16 is a cross section through a modified form of wheel head, and taken at right angles to the axis of the grinding wheel;

Fig. 17 is an axial section of the wheel head shown in Fig. 16;

Fig. 18 is an end view of the wheel head of Figs. 16 and 17 with the dust seal and dust cover removed therefrom;

Fig. 19 is a fragmentary transverse section through the wheel head of Figs. 16 to 18 and showing particularly a cylindrical slide used in displacing the wheel transversely of its axis;

Fig. 20 is a more or less diagrammatic plan view of one form of grinding machine constructed in accordance with the present invention;

Fig. 21 is a drive diagram of the machine shown in Fig. 20;

Fig. 22 is a view showing a partial axial section of a grinding wheel, and illustrating the principle of operation of the wheel dresser constructed according to the present invention;

Fig. 23 is a fragmentary normal section along the line 23—23 of Fig. 22, looking in the direction of the arrows;

Fig. 24 is an axial section of a wheel dressing or truing device constructed in accordance with one embodiment of my invention, the section being along the drawing plane of Fig. 23;

Fig. 25 is an end view taken from the left of Fig. 24 and showing the adjustable part of the dresser which holds the diamond;

Fig. 26 is a fragmentary section similar to Fig. 24 illustrating a modified construction;

Fig. 27 is a development to a plane of a part of the circumference of a cam used in dressers constructed according to my invention, and showing this cam in contact with an abutment or follower;

Fig. 28 is a diagrammatic sectional view of a device constructed according to the present invention for dressing or truing opposite sides of a grinding wheel simultaneously;

Fig. 29 is a diagrammatic view, partly in section, of a modified form of dressing or truing device, for dressing or truing both sides of a grinding wheel of curved axial profile; and

Fig. 30 is a diagram corresponding to Fig. 29 illustrating an operative connection.

Referring now to the drawings by numerals of reference, 35 denotes a helical gear; and 36 denotes the axis of this gear. In conventional practice, the grinding wheel,

indicated in dotted lines at W, is set to the helix angle at the pitch radius of the gear, that is, to the helix angle at the pitch point 38 (Figs. 1 and 4). The point 38 lies on the central radius 59 which intersects the axis of the grinding wheel at right angles; and it is the intersection of this radius with the cylindrical pitch surface of the helical gear. As a result of this conventional setting position, the two opposite tooth normals which pass through the point 38 are what is known as contact normals. They contain the points of contact 39 and 40 between the grinding wheel W and the profiles of the opposite sides 41 and 42 of the helical teeth 43 of the gear. The points 39 and 40 are low on the tooth profiles 41 and 42, lower than the pitch point 38, that is, closer to the tooth bottom. This low position causes the two oblique lines 45 and 46 of grinding contact to have different axial positions. Line 45 is closer to the upper end 47 of the gear 35 than the line 46.

In grinding a tooth space, the work 35 and the grinding wheel W move in a helical path about the axis 36 relative to each other as the wheel rotates on its own axis. As regards relative positions and grinding contact, the helical motion can be considered performed entirely by the work 35. At one time, then, the gear end 47 will be in a position as shown by dotted lines 47'. In this end position only a small end portion of the grinding line 45 remains on the work while most of the grinding line 46 is still on the work. It is seen then that grinding contact ceases on tooth side 41 long before it ceases on the opposite side 42. In the middle region of the teeth, the grinding pressure on one side provides some direct balance to the grinding pressure on the opposite side. At the tooth ends, however, this balance is disturbed. The balanced support for the wheel ceases on one side of the tooth space with the end of grinding contact on the opposite side of the tooth space. The wheel tends to spring away somewhat under the grinding pressure from the side which is still being ground, and to leave a slight wave on that tooth surface. The crest of this wave projects outwardly from the true desired shape of the tooth. In any case there is a disturbance at the tooth end caused by the relative axial displacement of the two grinding lines 45 and 46. This disturbance is apt to cause gear noise and may also shorten the gear life.

In accordance with one phase of the present invention this deficiency is remedied by setting the grinding wheel W' (Figs. 2, 3 and 4) to a different angular position and by modifying its shape accordingly. The grinding wheel is set to a larger helix angle than the helix angle at the pitch radius of the gear. In the embodiment illustrated in Figs. 2 and 3 it is so set that the grinding lines 45', 46' pass through mean points 50, 51 of the tooth profiles in a transverse section, that is, in a section perpendicular to the work axis as indicated in Fig. 3. In this way the grinding lines 45', 46' have substantially equal axial positions. When the upper end 47 of the pinion is in the position 47' (Fig. 2), then, one half of each grinding line 45', 46' remains on the work. Contact ceases substantially at the same time on both sides. There is no unbalanced pressure between the two sides.

Helix angle setting

The determination of the angular setting of the grinding wheel will now be described so that the grinding lines 65 pass through mean points 50, 51. The tooth surface normals 52, 53, at points 50, 51 are first determined. On involute gears they are tangent to the base circles (not shown), as well known, and are inclined to the plane of rotation, that is, to the drawing plane of Fig. 70, 3, at an angle equal to the known base helix angle. Next their intersection points 55, 56 with the plane 57 are determined. This plane contains the wheel axis 60 and is parallel to the axis 36 of the work.

The axis 60 of the grinding wheel W' is the straight line connecting the intersection points 55, 56, for the

normals to a surface of revolution all pass through its axis. By fulfilling this condition as described, the normals 52, 53 are made contact normals, namely, normals which are common between the work and the grinding wheel.

The working surface of the grinding wheel

The working surface of the wheel is best determined by first determining the line of contact between the working surface of the wheel and a helical tooth side of the work 35. After the line of contact is determined, with all the contact normals along it, these contact normals and contact points are turned about the axis of the grinding wheel into a single axial plane of the grinding wheel. The contact points are then points of the grinding profile in this position, and the turned contact normals are normals to the grinding profiles.

As shown in Fig. 2 the contact normals 52, 53 do not intersect. However, there is one pair of contact normals which intersect. They intersect on a radial line 59 at a point 61 (Figs. 3 and 4). This point is located at such a radius $36-61=r'$ (Fig. 3) that the helix angle ψ' at said radius is equal to the helix angle setting of the grinding wheel determined above.

r' can be determined from the well known equation for the helix angle ψ' :

$$r' = \frac{L \cdot \tan \psi'}{2\pi}$$

Like all normals of a surface of revolution, the surface normal at each point of the line of contact intersects the axis of the grinding wheel or rotary cutter. To determine the contact position at a given radius of the helical tooth surface, the surface normal at that radius is moved in a helical path along the tooth surface until it intersects said axis. In this imaginary displacement along and about the axis of the helical surface, the original normal continues to be a tooth surface normal; and the point where it intersects the tooth surface in its final position is a point of contact between the tooth surface and the working surface of the grinding wheel. Other points, corresponding to different radii are similarly determined, to obtain a series of points defining the line of contact.

The line of contact can also be considered the normal projection of the wheel axis to the tooth surface. It can be demonstrated mathematically that it can also be considered the normal projection to the tooth surface of another straight line, which is located nearer the tooth surface and is more convenient for determining the line of contact. The contact normals all pass through this other line 62 (Fig. 2). It connects points 61 and 63 (Figs. 2 and 3). The latter point is obtainable by spacing a unit distance (1 inch) from point 61 on a line drawn through this point parallel to the gear axis 36, to point 65 (Fig. 2). From point 65 the distance u defined below is measured off on a line 65-63 parallel to the wheel axis 60. It is measured on the same scale as said unit distance.

$$u = \frac{r'}{R_c \sin \psi'}$$

Herein R_c denotes the radius of the grinding wheel to point 61, that is, center distance, C minus r' ($C-r'$).

The axial profile of the grinding wheel can be determined from the points and normals of the line of contact in the known manner above outlined. It can also be determined experimentally by rotating a disc of grinding wheel size adjacent a cutting edge lying in the given helical tooth surface, and which is given a helical reciprocation so that it describes a given helical tooth surface.

Since the grinding wheel and the gear teeth contact along oblique lines, the grinding wheel profile in the normal section (Fig. 4) is less curved than the convex

tooth profile. The said normal section is perpendicular to the direction of the teeth and contains the axis of the grinding wheel. It is also an axial section of the grinding wheel.

The difference between the profile curvatures of the grinding wheel and the work in the normal section can best be illustrated by the centers of curvature of the two profiles. 66, 66' (Fig. 4) denote the contact normals which pass through the point 61. The centers of curvature 67, 67', 68, 68' of the contacting profiles of this normal section lie on these normals. The tooth profile curvatures and the location of their curvatures centers 67, 67' are known. The curvature centers 68, 68' of the wheel profiles can be obtained from the wheel profiles as determined above. The distances of the curvature centers of the wheel profiles, from the curvature centers 67, 67' of the tooth profiles depend on the wheel radius R_c to point 61, on the helix angle setting ψ' , and on inclination φ' of normals 66, 66' to a plane 69 perpendicular to radius 59. Distance $\Delta\rho$ is equal to 67-68 (67'-68') can be shown to amount approximately to:

$$\Delta\rho = R_c \tan^2 \psi' \sin \varphi'$$

This distance $\Delta\rho$ increases with increasing wheel radius. The larger the wheel, the more its profile approaches the profile of a rack which in the involute gear system is straight.

In the drawings, the wheels are shown small enough to keep them within the drawing space provided. Larger wheels are preferably used in practice.

Instead of aligning the axial positions of the grinding lines 45', 46' completely, it is also possible to align them only partially. Thus, the mean points of contact 50', 51', may be assumed in a normal plane (Fig. 7) rather than in a transverse plane perpendicular to the work axis as was done in Figs. 2 and 3.

On the larger member of a gear pair with corrected tooth proportions, that is, with shortened addendum and lengthened dedendum, the two grinding lines are often sufficiently aligned in the conventional procedure so that they do not require my special procedure just described. In general, the special procedure described results in an improvement of the gear pair by improving either one or both members. It represents the preferred procedure and can be practiced without any change in machine structure.

Tooth ease-off

Another and very important feature of the present invention is the procedure to attain the desired form of tooth ease-off or localization of tooth bearing. The teeth are eased off near their boundaries, lengthwise and profilewise, so that they bear over a localized area when run at light load in their exact position. Slight changes in the mounting, deflection under load, inaccuracies even within tolerances, displace the bearing area on the tooth surface, but with properly eased-off teeth, the teeth will never bear hard at their ends. Without ease-off this may occur. Tooth ends are then more apt to break off under fatigue and noise is more apt to develop. The result is that eased-off teeth are stronger and better.

Referring first to the lengthwise ease-off only, without profile ease-off, a generally square or rectangular bearing area is desired. This is shown at 70 in Fig. 5. It is the area between the straight lines 71, 71'. 45'' is the line of grinding contact in the mean position. Dotted lines 45₁ and 45₂ are lines of grinding contact on opposite sides of line 45'' and are generally similar to line 45''.

In the known methods of grinding ease-off the wheel is moved slightly depthwise adjacent both ends of the teeth. There is no depthwise motion at the middle of the teeth. This procedure is satisfactory on straight teeth; but on helical teeth it produces a form of ease-off different from the one intended. The ease-off follows

the line of grinding contact. At zero profile ease-off, the localized tooth bearing obtained in this known method is an area like the one bounded by lines 45₁ and 45₂. It is at a bias. Too much stock has been removed at the diagonal corners 73, 73', and not enough at the diagonal corners 74, 74'.

We can plot the ease-off at the various points of the tooth surface by connecting points of equal ease-off, thereby obtaining a geodetic map of the ease-off surface. Line 45'' is a line of zero ease-off. If lines 45₁ and 45₂ 10 are considered lines of constant and equal ease-off, then their inclination or slant depends to some extent on the curvature of the wheel profile. But in any case their averaged slant is substantially equal to the slant of line 45''. Heretofore, there has been no known way of 15 avoiding the bias condition.

The present invention, however, permits of attaining a localized bearing area as bounded by lines 71, 71' when only lengthwise ease-off is considered, and an oval area 75 such as shown in Fig. 6 when profile ease-off is added. Further, any form of bearing area may be attained, whatever may be held desirable. The method of the present invention provides full control of the bearing area. It can be kept free of slant as normally desired, or it can be slanted one way or the other. The present invention 20 enables full control as to where to place the ease-off, and how much of it to provide.

Principles of controlled tooth ease-off

The explanatory diagrams Figs. 8 to 11 can be considered a partial development to a plane of a cylindrical mid-section laid through the gear teeth. The axis of this cylindrical sectional surface coincides with the gear axis 36. The section may be taken along the pitch cylinder of the gear. In other words, the figures show developed portions of the peripheral surface of the gear. For clarity, the sections have not been cross-hatched.

In Fig. 8, 77 denotes the grinding wheel section in the mid-position of the grinding wheel. Its axis is parallel to line 78 and above it. If no ease-off were provided, the considered cylindrical surface would intersect the tooth sides in helices. These show up in the development as straight lines 79 in Fig. 8. With ease-off, the developed intersection lines with the tooth sides are convex curves 80 tangent to lines 79. Their curvature is very much exaggerated. At the tooth ends, the curves 80 have a normal separation z from their mean tangents 79, which on gears of the size of automotive transmission gears, amounts to something in the order of 0.001 inch. This is at a distance s from the point of tangency with a line 79, which distance depends upon the length of face F and on the helix angle ψ of the gear.

$$s = \frac{F}{2 \cos \psi}$$

At the small amount of z considered, the separation z and distance s are tied up with the radius R_m or curvature radius like the ordinates of a parabola, namely,

$$z = \frac{s^2}{2R_m}$$

and

$$R_m = \frac{s^2}{2z}$$

This determines radius R_m . Each arc 80 has a varying inclination to the direction of its tangent 79. It is zero at the middle and increases toward the ends. At the tooth ends the inclination t of a curve 80 to its mean tangent 79 amounts to:

$$\text{Arc } t = \frac{s}{R_m} \text{ in radians}$$

This can be transformed into:

$$\text{Arc } t = \frac{2z}{s}$$

The wheel position for generating the eased-off tooth end will now be determined, first for grinding a single side. For this reference will be made to Figs. 9 and 10. The dotted section 77 again represents the grinding wheel position for grinding truly helical tooth sides 79 without ease-off. At the upper end of the tooth space contact has shifted in the direction of the gear axis 36 from a mean position 81 to end point 81'.

To obtain satisfactory eased-off teeth we must keep the pressure angle constant along each side of a tooth space from end to end of a tooth.

To form the eased-off tooth ends, the grinding wheel is, as in conventional practice, fed depthwise into the work as it travels from a central position lengthwise of the work to either end of a tooth space. But as indicated by section 77_e, the wheel should contact curve 80 immediately adjacent point 81'. Only then will it be possible to retain the same inclination of the tooth surface normal to the cylindrical surface as on the true helicoid. The preservation of this inclination or pressure angle is a prerequisite to attaining the desired shape of the tooth bearing areas indicated at Figs. 5 and 6. We want to change the helix angle at the tooth ends but to preserve the pressure angle.

To keep the grinding contact immediately adjacent point 81' we have to put the grinding wheel in such a position that its sectional profile 77_e has the same inclination immediately adjacent point 81' as curve 80. This object could be attained in different ways if the wheel were grinding only one side of a tooth space at a time. 30 The wheel could for instance, be slightly turned about any axis passing through 81' and contained in the normal plane perpendicular to the tooth direction. None of these turning adjustments would affect the pressure angle. In other words, an infinitesimal turning adjustment of this kind would cause a pressure angle change which is infinitesimal in the second order, and is entirely negligible.

One position of the turning axis fits both sides of the tooth space equally well and results in simplicity besides. This axis is parallel to the axis of the grinding wheel, and may also pass through point 81'.

Fig. 9 shows its effect. The tooth surface normal 81'—82 before ease-off is inclined to the drawing plane of Fig. 9 at what may be called the normal pressure angle at 81' so that the end point 82 is below the drawing plane. The turning axis 85 lies in the drawing plane. As normal 81'—82 is turned about axis 85 its point 82 describes a circle which is projected as a straight line in Fig. 9. Point 82 thereby moves to a position 82' so that normal 81'—82' is perpendicular to curve 80. In this new position of the normal its inclination to the drawing plane has not changed at all. Through this turning adjustment the grinding wheel is now capable of contacting curve 80 immediately adjacent point 81' as required. The turning displacement on axis 85 moves the wheel axis to a position 60'.

In addition to this turning displacement a linear displacement of the wheel with respect to the work is required to advance the wheel outline a distance z over point 81'. In the present case this advance is best obtained by a depthwise displacement z_d which depends on the inclination of the tooth normal, or the normal pressure angle φ at point 81', as follows:

$$z_d = \frac{z}{\tan \varphi}$$

Thus at the tooth ends, the grinding wheel should be relatively advanced depthwise an amount z_d and it should be relatively turned on an axis 85 through an angle which

produces the required helix angle change t , and which amounts to:

$$t_d = \frac{t}{\tan \varphi} = \frac{s}{R_m \tan \varphi} \text{ in radians}$$

Both of these displacements move the wheel further into the work so that the outline 77_e of the wheel in the drawing plane of Fig. 9 becomes larger.

The same is true for the opposite side of the teeth which is referred to in Fig. 10. The points 81_a, 82_a, 82'_a, and the line 85_a in Fig. 10 correspond to the points 81, 82, 82' and the line 85, respectively in Fig. 9, but relate to the opposite side of the tooth space. The described conditions apply also when both sides of the tooth space are ground simultaneously. This desired case is illustrated in Fig. 11 where the grinding wheel is also shown near one of the two end positions.

The distance b of the projected wheel axis 60' from turning axis 85 in Figs. 8 to 10 amounts to the product of the wheel radius R_c to point 81' and turning angle t_d . It is:

$$b = \frac{R_c s}{R_m \tan \varphi}$$

This is further shown in Fig. 12 which is a view along the axis of the grinding wheel. Dotted line W₁ shows the grinding wheel periphery in a position to grind teeth without ease-off. Full line position W' shows the actual grinding position. The wheel is fed in depthwise a distance z_d so that the wheel axis is displaced from position 60 to position 60_a. Simultaneously it is turned on axis 85 through the above defined angle t_d whereby the wheel axis is displaced from position 60_a to 60'. It has then a distance b from the plane 60—85. Its depthwise distance z_t from the initial position 60 is made up of a distance z_d and of the depthwise elevation of position 60_a over position 60'. The latter is:

$$\frac{1}{2} t_d^2 R_c$$

After transformation the total amounts to:

$$z_t = z_d \left(1 + \frac{R_c}{R_m \tan \varphi} \right)$$

These two displacements b and z_t can be obtained in accordance with my invention by moving the grinding wheel axis 60 about an axis 87 (Fig. 12) parallel to axis 60. Radius $r_x = 60—87$ and the turning angle θ about axis 87 has to fulfill the equations:

$$\begin{aligned} z_t &= \frac{1}{2} \theta^2 r_x \\ b &= \theta r_x \end{aligned}$$

By division

$$\frac{z_t}{b} = \frac{1}{2} \theta$$

and

$$\theta = \frac{2z_t}{b}$$

Hence, also,

$$r_x = \frac{b}{\theta} = \frac{b^2}{2z_t}$$

This determines pivot 87 and the point of swing θ about it.

The swing is in one direction at one end of the tooth space and in the opposite direction at the other tooth end. As the wheel goes through a grinding path from one tooth space end to the other, the swinging motion about axis 87 is continuously in one direction. The swinging position moves from an angle $(-\theta)$ to zero and to $(+\theta)$. It is proportional to the stroke. Some overtravel should be had.

The above described procedure produces the desired bearing without bias providing the grinding wheel and the work are very rigidly mounted.

Bearing changes can be made by altering the data z_t or b , and determining r_x and θ over again. A reduction in b tends to slant the tooth bearing toward the direction of the line of contact 45" (Fig. 5). An increase in b tends to slant it in the opposite direction.

There may be an occasional demand for an ease-off which starts only adjacent the tooth ends, and which leaves the middle portion of the helical teeth entirely unaltered and without ease-off. The curve 80 (Fig. 8) would then be composed of a straight middle portion coinciding with the tangent 79 and of curved end portions. This kind of ease-off can also be attained in accordance with the present invention. In this case the swinging motion of the wheel on axis 87 (Fig. 12) is not proportional to the stroke distance. Instead it stops at the middle of the stroke. The swinging motion is interrupted by a dwell at the middle portion.

Fig. 13 shows diagrammatically the gist of the method of obtaining a controlled tooth ease-off in accordance with the present invention. It comprises feeding the wheel in relative to the work substantially in proportion to the square of the distance s from the mean point, and in also changing the grinding wheel position so that grinding contact with the lengthwise tooth curves 80 can be effected immediately adjacent a line parallel to the gear axis 36. The two end points of the curve 80 are then ground in positions displaced from one another in the direction of the gear axis. While this is true for the grinding points themselves, the corresponding point of the wheel axis moves differently. This point will be referred to as the wheel center. It will be defined as the intersection with the wheel axis of a plane perpendicular thereto and containing the mean point of the grinding profile, the point which produces the mean point of the gear tooth profile.

This definition applies to grinding wheels for grinding one side of the teeth. On wheels for grinding both sides of the teeth the wheel center is the average of the two individual centers as above defined. The wheel center 89 in Fig. 4 then lies in the plane 90 of symmetry of the wheel, and is its intersection with the wheel axis 60.

In the diagram Fig. 13 the grinding wheel is defined by its plane of symmetry 90, by its axis 60, and by its wheel center 89. 91 denotes the middle of the grinding area 45 on the gear 35 defined by its outline and its axis 36. The projected distance 89—91 equals the distance b in the end positions above referred to.

As the middle of the grinding contact area moves from 91_a to 91 and to 91_b in the axial direction of the work, the wheel center moves from 89_a to 89 and to 89_b along a line 92 inclined to the direction of the gear axis 36. In the preferred embodiment the swinging motion of the grinding wheel on axis 87 is continuous during a grinding pass.

In accordance with the present invention the wheel center moves relative to the work in a direction inclined to the direction of the work axis, while describing a curve concave toward the work, and while the work turns on its axis. The direction 89_a—89_b lies between the direction of the work axis and the direction of the teeth. The latter coincides with the direction of the plane 90 of symmetry.

The above applies also when the wheel center is offset laterally on the wheel axis and is at point 93. 93_a—93—93_b indicates the path of such a wheel center.

The determination of the wheel profile for grinding truly helical teeth without ease-off has been described above. To attain profilewise ease-off on the teeth the so-determined profile is slightly altered to take off more stock 70 at the profile ends as readily understood.

Structure for attaining controlled ease-off

Figs. 14 and 15 illustrate one embodiment of a wheel-supporting and wheel-actuating mechanism for carrying out the method just described.

The grinding wheel W' is here secured to a shaft 95 in conventional manner. This shaft is rotatably mounted in a holder 96 which is radially adjustable in a pivot member 97. This member is adapted to swing in time with the working stroke by means such as shown in the embodiment of Fig. 16. It is split lengthwise into two halves 97', 97'' which are bolted together by bolts 98. It is pivotally mounted in a wheel head 99 in two spaced bearings 100, 100' which may be anti-friction bearings if desired.

Holder 96 is radially adjustable in pivot member 97, spaced screws 101 being provided for this purpose. These screws thread into nuts formed integral with the bevel gears 102. These gears are journaled in the pivot member 97, and are turned simultaneously by pinions 103 which are rigid with a common shaft 104. The two end screws 101 are rigid with slideable holder 96. The middle screw 101 bears against an elastic disc 105 and serves to secure the radial position of the holder resiliently so that all the screws are under load always and do not tend to shake loose. The shaft 104 is journaled in projections of the lower half of the pivot member. It is secured in a desired turning position by known means (not shown) and is accessible from the outside through a hole 107.

The adjustment of holder 96 is to offset the wheel axis 60 from the axis 87 to secure the desired localization of tooth bearing. The wheel head 99 is adjustable for helix angle on ways 110 about an axis 111 (Fig. 15). Ways 110 are curved about this axis.

Flexible dust seals 112 are used to protect the inside of the wheel head from grit. Shaft 95 and the grinding wheel W' mounted thereon are rotated by a V-belt acting on pulley 113.

A further embodiment of a wheel head is shown in Figs. 16 to 19.

Here the adjustment of the holder in the pivot member is made use of for withdrawing the wheel from the work. The wheel is preferably withdrawn from the work after each grinding stroke, and it is advanced to working position again prior to each grinding stroke. In accordance with the present invention this advancement and withdrawal, the clapping, is preferably made in the same direction as the adjustment of the holder for eccentricity to the pivot axis, and is made with respect to the pivot member.

The shaft 95 of the grinding wheel is here rotatably mounted in a holder 115 which has two spaced gears 116 and 117 rigid with it. These gears are coaxial with shaft 95. Gear 117 is seen also in Fig. 18. The tooth profiles of the two gears are alike. The teeth may be helical, and they are then of opposite hand on the two gears. Each of the two gears meshes with a rack rigidly secured to a pivot member 118. One such rack is seen in Fig. 18 and denoted at 119.

Intermediate the two gears 116, 117 the holder rotatably carries a sliding block 120 made up of two parts 120', 120'' (Fig. 16) rigidly secured together. The sliding block is rotatable on the holder 115 on an axis coinciding with the axis of shaft 95 and of grinding wheel W' . It is adjustable radially in a rectangular opening 121 provided in a part 122 which during grinding is fixed relative to the pivot member 118. Adjustment is made by turning the square end of a screw 123 which is rotatably held in said opening. In this adjustment the axis 60 of shaft 95 is radially offset from the axis 130 of the pivot member 118. In this radial adjustment the two gears 116, 117 roll on their respective racks 119, and because of their ample axial distance from one another they maintain the holder 115 exactly parallel to its initial position and parallel to the axis of the pivot member. Backlash is avoided during the grinding passes by pressing the gears depthwise into their racks as will further be described.

The pivot member 118 is mounted for oscillation on its axis 130 in two spaced bearings 131, 132 (Fig. 17) pro-

vided in the wheel head 133. While the bearings shown are plain bearings they may also be made anti-friction bearings if desired. The wheel head 133 is adjustable angularly for helix angle about axis 111.

Part 122, which has the rectangular opening, is made up of two component parts 122', 122'' (Fig. 16) rigidly secured together by means not shown. Part 122' contains a cylindrical outside surface 134 which during the grinding passes is engaged by a stop 135 (Fig. 16). In this position the cylindrical surface 134 is coaxial with the axis 130 of the pivot member 118. Rocking motion on the pivot axis 130 then leaves the position of the cylindrical surface unaffected. It does not move in, nor does it move out through the rocking motion.

Part 122 is slideable in a transverse cylindrical hole 136 provided in the pivot member 118. The hole 136 extends in the direction of the pitch planes of the racks. As the part 122 moves to the right in hole 136 it carries the holder 115 and the grinding wheel with it. Thereby the gears 116, 117 roll on their racks. The grinding wheel then recedes depthwise from the work, and gets clear of the work. The reverse occurs before the start of a grinding pass.

The periodic advance and withdrawal of the grinding wheel to and from working position, the clapping, is effected by a cam 140. This cam is rigid with a shaft 141 which is mounted in the wheel head 133, and which is geared to perform one complete turn between successive grinding passes. This cam engages the cylindrical surface 134, except during grinding engagement itself, where there is a very slight clearance between said surface and the cam. The position of part 122 is then determined by stop 135 (Fig. 16).

Engagement between part 122 and stop 135, or part 122 and the cam 140 is maintained by a spring 142 (Fig. 16). This spring acts on a lever 143 rotatably carrying a roller 144. Roller 144 bears against a cylindrical surface 145 provided on part 122''. In the forward position, when the part 122 engages the stop 135, surface 145 is coaxial with the pivot axis 130.

The part 122 is pressed against stop 135 during grinding. The stop exerts a pressure which is substantially normal to the cylindrical surface 134 and which contains a large downward component. The part 122 is made sufficiently free or loose in the cylindrical bore 136 so that the downward pressure is transmitted to the holder 115 rather than to the bore. Thereby the gear teeth of the holder are pressed tightly into the teeth of their racks to keep the whole unit rigid during grinding.

Shaft 141 is rotated by a worm wheel 146 by means of a drive which passes through the adjustment axis 111 and which in Fig. 17 is indicated by a dotted line 147.

The required timed rocking motion on pivot axis 130 for localization of tooth bearing is effected by a cam 150 secured to shaft 141 at one end. This same shaft holds cam 140 at its opposite end. Cam 150 engages a roller 151 (Fig. 18) mounted on the pivot member 118. Engagement between cam 150 and roller 151 is maintained by the spring 152 indicated in dotted lines in Fig. 16. Cam 150 is easily accessible and can be changed readily.

General structure

Either a vertical or a horizontal disposition of the work axis may be used. In Fig. 20 I have shown as an example a vertical disposition. The work 35 is rotatably mounted on a slide 156 which is radially adjustable along ways 157 provided on the base 158. This adjustment is to bring the work into and out of operative engagement with the grinding wheel.

The grinding wheel W' is mounted in a holder radially adjustable in a pivot member, as described, which is disposed inside of a wheel head 133. It is driven from a motor 160 mounted on the wheel head 133 on the opposite side of the grinding wheel. The drive is by a belt 161 to a pulley 162 secured to a counter shaft 163

also mounted in bearings rigid with the wheel head. Another pulley 164 on shaft 163 drives the pulley 113 (Fig. 15) of the wheel spindle through a belt 165. This belt is shown in this diagrammatic view as a plain belt rather than a V-belt. The belt 165 passes over a tension pulley 166 which is movable about shaft 163 and is kept pressed against the belt by spring means not shown. In this way a safe drive to pulley 113 is effected from a shaft with a fixed axis even though the pulley 113 partakes of a small rocking motion.

The wheel head 133 is mounted on a slide 167 for adjustment about an axis 111 in accordance with the helix angle of the work. The slide 167 is vertically adjustable in the direction of the work axis along guides 170. This adjustment is to locate the position of axis 111 relative to the work. The slide 167 may also be used for reciprocation if desired.

Preferably grinding is effected during the stroke in one direction only and the work is indexed between successive grinding strokes. Whether the linear stroke along the work axis is performed by the wheel or the work is a matter of choice. On large gears the wheel is preferably reciprocated axially of the work.

One simple way of grinding helical teeth is by rotating the work at a uniform rate during the whole of the grinding process. The work turns through an integral number of teeth between successive grinding passes. To avoid complications this integral number is preferably kept prime to the number of teeth of the work.

Fig. 21 shows a drive diagram of the feed motions. Motor 172 imparts rotation to a sleeve 173 through change gears 174. The sleeve 173 drives a shaft 175 mounted on the slide 156 shown in Fig. 20. Shaft 175 drives worm 176 through change gears 177. The worm 176 meshes with a worm wheel 180 coaxial with the work.

If the linear strokes are imparted to the grinding wheel then the dotted rectangle 181 represents a known stroke mechanism which is driven from the sleeve 173 through gears 182. The gears 182 further operate through other gears 183, 184 to impart motion to a shaft 185 mounted in the wheel head. Shaft 185 imparts motion to the cam shaft 141 (Fig. 17) through a worm 186 and wheel 146 to turn it at a rate of one turn between successive passes. Shaft 141 thus turns around completely as many times as there are strokes. Thus the pivotal support for the wheel is oscillated once per stroke of the wheel through cam 150; and the wheel is moved into engagement with the work prior to a grinding stroke and withdrawn from engagement with the wheel at the end of each grinding stroke by operation of cam 140.

Dotted rectangle 190 represents a known indexing mechanism. With such a mechanism it is possible to grind straight teeth on a given grinding machine and thus extend its range. An indexing mechanism also has use on helical teeth in modified procedures. If the stroke is to be performed by the work then the rectangle 190 also represents a known stroke mechanism in addition to an index mechanism. Of course, there is only one stroke mechanism. If the work is reciprocated there is no need for reciprocating the grinding wheel.

My described method and means for applying controlled tooth ease-off can be used with any one of heretofore known methods of grinding helical gear teeth with a grinding wheel of curved, or even straight, axial profile. The ease-off may be applied to either one or both members of a gear pair.

The wheel dressing and truing device

The wheel dresser has not been shown on the diagrammatic drawings of Figs. 20 and 21. A preferred form of wheel dressing and truing mechanism will now be described. Its principles are illustrated in Figs. 22 and 23.

The end diamond 200 merely serves to dress off the periphery of the wheel W'. If the tooth space bottom is left unground a straight dressing pass is sufficient. Otherwise the corners of the wheel profile should be rounded off in known manner.

The side dressing diamonds 201, 202 have to dress the curved side profiles 204, 205 of the wheel. These profiles usually have varying curvature, being more curved adjacent the point of the wheel than further back. This is illustrated by the circle 206 which is the circle of curvature at the mean point 207 of the active grinding profile. The profile 204 hugs the curvature circle 206 very closely adjacent point 207, then extends outside of it further back on the wheel, while more toward the point of the wheel it tends to reach inside of the curvature circle. Non-circular curve 204 has an evolute 208 (Fig. 22) and is generally similar to an involute. 209 denotes the surface normal at point 207. The tangent plane at point 207 to the wheel surface is perpendicular to the surface normal.

In accordance with my invention the diamond point, which in one position coincides with the point 207, is turned about a dresser axis 210 (Fig. 23) inclined at an acute angle to the wheel surface and to said tangent plane and passing through the mean normal 209. The axis 210 lies in the drawing plane of Fig. 23 and is so positioned that at point 207 the diamond moves in the direction of the axial wheel profile. The direction of the motion at point 207 lies in an axial plane of the wheel.

As the diamond turns on dresser axis 210 it describes a circle about said axis. This circle shows up as a straight line 211 in Fig. 23. Shown with exaggeration the diamond moves from a position 207 to a position 212.

As the described circle does not lie exactly on the desired surface of the grinding wheel, the dresser is advanced along its axis 210 to compensate for the difference. The diamond thereby moves from a position 212 to a position 213 (Fig. 23) which corresponds to a point 213' of the grinding wheel profile (Fig. 22). When the diamond motion is tangent to an axial plane at point 207, as described, the dresser axis 210 intersects the surface normal 209 at the curvature center of the axial profile that would be produced on the grinding wheel without motion along the dresser axis. This can be demonstrated mathematically.

In accordance with my invention the dresser is so adjusted that its axis 210 intersects the surface normal 209 in the center of curvature 215 of the required grinding wheel profile. Without any axial advance of the dresser 50 the diamond would then produce a substantially circular wheel profile which has the same curvature radius 207—215 as the wheel profile requires. Then the axial motion of the dresser has to make up only for the slight difference between the profiles of the same mean curvature radius.

To attain a curvature center 215, the dresser axis 210 is set to pass through this center. Should a curvature center 215' be required, then the dresser axis is set to the dotted position 210' where it passes through point 215'.

The axial motion of the diamond is controlled by means 60 of a cam and follower, one of which is held stationary, and the other of which is rigid with the diamond carrier. In the embodiment specifically illustrated the cam is the stationary member. It is a face type cam. As the swing of the diamond carrier is limited, only a fraction of the entire circumference of the cam is swept by the follower. It is therefore feasible to put several cam profiles on the same cam member.

Fig. 27 is a partial development of the cam. Follower 220 contacts the cam profile 221 at a point 222 which 70 corresponds to the position of the diamond at the mean point 207 of the active grinding profile. As the dresser is set to dress the required profile curvature at point 207 even without axial motion, the cam 221 has to provide very little axial motion in that region. 222 is a point 75 of inflection on the cam profile. When the follower 220

turns from right to left in engagement with the cam profile it moves up or forward axially until it reaches the proximity of point 222. There its axial motion stops briefly, and then gradually continues in the same forward direction. More broadly its minimum axial motion is at the mean point 222, and it moves in the same direction axially on both sides of this point, as it swings over the cam profile from one end of swing to the other end.

The above characteristic of the cam profile can be expressed in mathematical terms using the profile tangent at point 222 as one axis of a coordinate system, and the vertical direction as the other axis, point 222 being the origin. The ordinate y is then the distance of a given profile point from the profile tangent at the point of inflection 222. And the lateral distance of the profile from origin 222 is the abscissa x . It is measured in the direction of the profile tangent at the origin 222.

The cam profile can then be expressed by the following equation: $y = Cx^3$, where C is constant. This omits possible higher orders, that is, terms where x appears at a higher power than the cube.

In accordance with the present invention, the profile curvature is automatically changed very gradually as the wheel diameter changes through repeated dressing and truing. As pointed out, a concave wheel profile should become more curved as the wheel diameter is reduced to produce a constant profile on the helical teeth. This is done by tying up the turning position of the cam 221 with the diameter of the grinding wheel, that is, with the position of the dresser slide which is adjustable radially toward the grinding wheel.

It will now be shown that small changes of the turning position of the cam result in small changes of the curvature radii produced on the wheel profile. Let it be assumed that the cam is so set that a point of the cam profile with abscissa dx contacts with the follower 220 while the diamond is at the mean point 207 as before. The abscissas correspond to turning angles from the new mean position on the cam. They now amount to:

$$x' = (x - dx).$$

Hence $x = (x' + dx)$ and

$$y = C(x' + dx)^3; \text{ and:}$$

$$C(x' + dx)^3 = Cx'^3 + 3Cx'^2dx + 3Cxdx^2 + Cdx^3$$

As dx is very small, the terms in dx^2 and dx^3 are negligible as compared with the terms in dx . Thus we obtain:

$$y = Cx'^3 + 3Cxdx^2$$

at the small amounts of dx considered.

As will be recognized, the term in x'^2 results in a change in curvature of the path described by the diamond, and of the curvature produced on the wheel profile. It is seen then that a small change in the cam timing effects primarily a curvature change on the wheel profile.

Structure of the dressing mechanism

Referring particularly to Fig. 24, diamond 201 is mounted in a small cylindrical part 225, which in turn is securely held in holder 226 by a screw 227 that threads into said holder.

A side view of the holder is seen in Fig. 25. It is adjustable toward and away from the grinding wheel along the line 230 which may coincide with the wheel surface normal at the mean point of the working profile of the wheel. Diamond 201 is shown at this point.

The holder 226 is adjustably mounted in an opening provided in a pivoted part 231. For adjustment, a tool may be used which engages a threaded hole 232 provided in the holder. The holder is secured in any adjusted position by a screw 233 with a square end. This screw threads into the threaded hole provided in the pivoted part 231 and acts on the holder through a cylindrical pin 234 with an inclined plane end 235. This end

contacts the adjacent plane side 236 (Fig. 25) of the holder. An elastic disc 237 is interposed between the screw 233 and pin 234 to maintain pressure at all times and to thereby secure screw 233 against accidental rotation.

Part 231 has a pivot axis 210 inclined at an acute angle to the holder 226 and to the line of adjustment 230. Axis 210 intersects the line 230. The pivoted part 231 is mounted for oscillation about and motion along its axis 210 in a housing 240, being journaled on two spaced bearings 241, 242. The front bearing 241 extends around the holder 226. This bearing is cut off in front at an angle so that the bearing portion around its periphery has varying axial positions. The upper portion 241 is farther advanced axially. The other bearing 242 is a more conventional bearing. It is disposed at the rear. By using a front bearing 241 which extends partly beyond holder 226 a sufficient spread of the two bearings is obtained for mounting the pivoted part 231 rigidly in a confined space.

A sleeve 245 is threaded onto a stem 246 of the pivoted part 231 and fits about the cylindrical portion 247 of this stem. Sleeve 245 contains a cam follower 220, and its cylindrical outside surface 250 serves as a bearing surface in bearing 242. A coil spring 251 is inserted between a shoulder 240' of housing 240 and an opposed shoulder on the outside surface of sleeve 245. This spring presses the follower 220 against the cam 252 whose cam profile has already been described.

After partial assembly, the sleeve 245 is secured against turning motion on the stem 246, for instance, by a pin extending through coaxial holes 253 of the stem and sleeve, or in any other suitable known way.

Pivoted part 231 contains helical teeth 254. They engage rack teeth rigid with a hydraulic piston not shown in Fig. 24 so that the pivoted part may be oscillated by such conventional hydraulically actuated means.

Face cam 252 contains teeth 255 on its outside, which are engaged by matching teeth provided internally in a ring member 256. These teeth serve for coupling, that is, rigidly connecting the cam and ring member 256.

The ring member is maintained stationary in the grinding operation; but it is turned when the dresser slide (not shown in Fig. 24) is advanced toward the wheel axis. To this end it is mounted on the housing 240 by means of a ball bearing 257 with double contact. The ring member further contains the worm wheel teeth 260 for engagement with a worm not shown in Fig. 24. An end plate 261 is rigidly secured to the ring member 256 and holds the cam member axially.

The dresser or truing apparatus obviously will be protected from dust by conventional dust seals. I have shown, however, a seal 262 at the front because of its more unusual construction. It is a flexible seal made for instance of synthetic rubber bonded to the conical front end 263 of part 226. At its other end it is secured in grooves 264 provided on housing 240 by a clasp 265 of known construction.

Even without the provision for changing the cam timing, this dresser has merit. It is simple and it maintains the diamond at a nearly constant angle to the grinding wheel surface. This makes it possible to use diamonds other than those lapped to a single sharp point.

The dresser shown in Fig. 26 has no adjustment for changing the cam timing. Here the cam is formed on the hub 270 of a flanged member 271 which is bolted directly to the housing 240'. I have shown here a square projection 272 on the stem 246' of pivoted part 231. It permits hand operation with a suitable tool should such hand operation be desired. The preferred operation is however by hydraulic means as in the dresser of Fig. 24.

One way of arranging a pair of dressers is indicated in Fig. 28. The dressers are of the type described but are more diagrammatically shown than in Figs. 24 and 26.

Each holder 226 is adjustable toward and away from the grinding wheel in a pivoted part 231, preferably along the mean surface normal 275. The pivoted part contains a cam follower 220 engaging a face cam 252.

The pivoted part 231 is mounted in a housing 240 formed integral with or rigid with a slide 276. This slide is here mounted on a circular slide 277 for adjustment in the same direction 275 as the holder 226. The circular slide can be adjusted angularly for pressure angle about a pin 280 whose axis is perpendicular to line 275 and intersects the pivot axis 210 at an acute angle. The circular slides 277 of the two opposite dressers are adjustable about their pins 280 on a common slide 281, to which these pins are secured. This common slide is adjustable in a straight line to move the pair of dressers radially toward or from the axis of the grinding wheel.

In this illustrated embodiment a ball linkage effects a change in the cam timing as the wheel diameter is reduced. The stationary ball joints 282 are located on a slide 283 adjustable in the same direction as the slide 281 but held stationary after initial adjustment. These joints are indicated by their external spherical portions only. Each cam contains another ball joint 284 at a given distance from its axis. The connecting link is indicated by the straight line 285. It is adjustable for length.

To effect an angular adjustment of each cam 252 upon adjustment of their common slide 281, the two joints of each link have to be at different vertical levels with respect to the drawing plane. If they were at the same level a moderate adjustment of the slide 281 would leave the cam timing practically as it was. The larger the inclination of the link axis to the drawing plane, however, the more adjustment of the cams will result at a given displacement of the common slide 281. The said inclination at the middle position of the common slide 281 can be set to the desired amount by adjusting slide 283, and then locking it.

Instead of the shown linkage I may also use the cam timing control described below.

The dressing and truing device illustrated in Figs. 29 and 30 differs from the dresser of Fig. 28 in that the pivoted parts 231 are set at a fixed inclination on a common slide 286 which is adjustable to move the dressers toward or from the wheel axis. The housing 240 is shown here merely by slide 287 with which it is rigid. The two opposite slides 287 are adjustable at right angles to the adjustment of the common slide 286, that is, in a direction parallel to the wheel axis. They are so adjustable directly on the common slide 286.

Fig. 29 shows diagrammatically one way in which the device may be operated hydraulically. The hydraulic cylinders 288 are rigidly secured to the common slide 286. A pair of pistons 289 formed in one piece are adapted to reciprocate therein. They act on a bar 290 through a joint 291. This bar is pivoted at its opposite end in a ring 292, which engages a sleeve 293. The latter contains internal threads. The thread on one side is a right hand thread. On the other side it is a left hand thread. The internal threads are engaged by the threaded ends of the racks 294 which engage helical teeth 254 (Fig. 24) provided on the pivoted parts 231. When the pivoted parts are locked, turning of sleeve 293 will move the opposite slides 287 equally in opposite directions at the same time.

Intermediate the ring 292 and joint 291 the bar 290 passes through another joint 295 which is similar to joint 291. This joint 295 is stationary and adjustable along the guides 296 in the general direction of bar 290. It serves as a fixed pivot for the bar but permits lengthwise movement of the bar.

Each of joints 291 and 295 comprises a cylindrical pivot 297 which is slotted to receive the bar 290. The outside surface of this pivot is rotatable in the cylindrical inside surface of a bearing portion (the bearing portions

of pistons 289 in the case of joint 291, for instance), which is recessed at both ends to clear said bar.

In the described construction the amount of swing of both pivoted parts 231 is simultaneously adjustable. To shorten the swing, joint 295 is adjusted toward ring 292. To lengthen the swing, said joint is adjusted away from ring 292. The position of the swing is also adjustable. After locking the slides 287 in their desired positions and leaving the pivoted parts free to turn, a turning adjustment of the sleeve 293 in one direction swings both pivot parts down. In this way the mean position of swing may be altered as desired.

The end diamond 200 (Fig. 22) may be made to move with ring 292 if desired.

As indicated in Fig. 24, the cam 252 is adjusted by means of the teeth 260 provided on a worm wheel rigid with the cam. Each worm wheel 260 meshes with a worm 298 (Fig. 30).

The worms 298 are rotatably mounted on the respective slides 287 and their shafts have splined connection with a worm wheel 299 having a long hub 300. A worm 301 meshes with the worm wheel 299. It is driven from the spindle 302 by means of change gears 303 indicated by their pitch circles only. This spindle is mounted on common slide 286 in an axially fixed position. It contains a screw (not shown) for adjusting slide 286 through engagement of said screw with a stationary nut.

As the common slide 286 is adjusted by turning spindle 302, the worms 298 are also turned in time therewith. They turn worm wheels 260, and thereby the cams 252 so that the dressed wheel profile becomes more curved as the wheel diameter is reduced in the amount required for grinding helical teeth.

The two worms 298 like the two cams 252 are of opposite hand to obtain the desired result simultaneously on both side dressers by rotating both worms in the same direction.

The described method of automatically changing the wheel profile with the wheel diameter permits of obtaining a constant product with a practical range of wheel diameters before a new set-up is required. It eliminates a defect of the conventional process.

While the invention has been described particularly with reference to grinding, it is understood, as previously stated, that the invention is applicable also to cutting of gears. The term "gear" as used herein is intended to include all forms of helically toothed members including worms.

Having thus described my invention, what I claim is:

1. The method of producing helical side tooth surfaces on a gear which comprises engaging a disc type rotary tool with a gear blank, and rotating the tool in engagement with the blank, while effecting a relative helical motion between the tool and blank about and in the direction of the blank axis, and while simultaneously effecting a further relative motion between the tool and blank in a plane which is perpendicular to the tool axis and which is inclined to the blank axis and in which the tool center travels in a path which is concave toward the blank.

2. The method of producing helical side tooth surfaces on a gear which comprises engaging a disc type rotary tool, that has opposite side working surfaces that are of curved profile in axial section and that are symmetrical to a central plane perpendicular to the tool axis, with a gear blank so that said plane is inclined to the axis of said blank, and rotating the tool in engagement with the blank while effecting a relative helical motion between the tool and blank about and in the direction of the blank axis to effect working passes of the tool longitudinally of the workpiece, and while simultaneously effecting a further relative motion between the tool and blank in said inclined plane which is continuous in one direction and without reversal during each working pass.

3. The method of producing helical side tooth surfaces on a gear which comprises engaging a disc type

rotary tool, that has opposite side working portions that lie, respectively, on opposite sides of a mean plane perpendicular to the tool axis and that lie, respectively, in separate surfaces of revolution coaxial with the tool, with opposite side tooth surfaces of a gear blank so that said plane is inclined to the axis of said blank, and rotating the tool in engagement with the blank while effecting a relative helical motion between the tool and blank about and in the direction of the blank axis, and while simultaneously effecting a further relative motion between the tool and blank in a direction approximately lengthwise of the engaged side tooth surfaces and about an axis which is offset from but parallel to the tool axis and which is offset from the tool axis in a direction approximately radial of the blank.

4. The method of producing helical surfaces on a workpiece which comprises engaging a rotary tool, that has working portions disposed in a surface of revolution extending about the tool axis, with the workpiece, so that a plane, which is perpendicular to the tool axis, is inclined to the axis of the workpiece, and rotating the tool in engagement with said workpiece while effecting a relative helical motion between the tool and workpiece about and in the direction of the axis of the workpiece, and while simultaneously effecting a further relative motion between the tool and workpiece in the direction of a mean helix of the engaged helical tooth surface to be produced on the workpiece and about an axis perpendicular to said main helix, the tool axis being offset from the last-named axis in a direction approximately radial of the workpiece.

5. The method of producing helical side tooth surfaces on a gear which comprises engaging a disc type rotary tool, which has opposite side working surfaces that are symmetrical with respect to a mean plane perpendicular to the tool axis, with a gear blank so that said plane is inclined to the axis of the blank, and rotating the tool on its axis in engagement with the blank, while effecting a relative helical motion between the tool and blank about and in the direction of the blank axis, and while simultaneously effecting a further relative motion between the tool and blank in a plane, which is inclined to the blank axis, in time with said helical motion and in which the tool center travels in a path which is concave toward the blank.

6. The method of producing helical side tooth surfaces on a gear which comprises engaging a disc type rotary tool which has opposite side working surfaces that are disposed at opposite sides of a mean plane perpendicular to the tool axis and that are of curved profile in an axial plane, with a gear blank so that said plane is inclined to the blank axis, and rotating the tool in engagement with the blank while effecting a relative helical motion between the tool and blank about and in the direction of the blank axis, and while simultaneously effecting a further relative motion between the tool and blank about an axis, which is perpendicular to the general direction of the engaged tooth surfaces, in time with said helical motion and in which the tool center moves in an arcuate path concave to the blank.

7. The method of producing helical surfaces on a workpiece which comprises engaging a rotary tool, that has working portions disposed in a surface of revolution extending about the tool axis, with the workpiece, so that a plane, which is perpendicular to the tool axis, is inclined to the axis of the workpiece, and rotating the tool in engagement with said workpiece while effecting a relative helical motion between the tool and workpiece about and in the direction of the axis of the workpiece, and while simultaneously effecting a further relative motion between the tool and workpiece about an axis parallel to the tool axis and offset therefrom in a direction approximately radial of the workpiece, in time with and substantially in direct proportion to, said helical motion.

8. The method of producing helical side tooth surfaces on a gear which comprises engaging a disc type rotary tool, which has opposite side working surfaces of curved axial profile symmetrical with reference to a mean plane perpendicular to the tool axis, with a gear blank with the tool inclined to the blank axis at an angle larger than the helix angle at the pitch radius of the blank, and rotating the tool in engagement with the blank, while simultaneously effecting a relative helical motion between the tool and blank about and in the direction of the blank axis.

9. The method of producing helical side tooth surfaces on a gear which comprises engaging a disc type rotary tool, which has opposite side working surfaces of curved axial profile symmetrical with reference to a mean plane perpendicular to the tool axis, with a gear blank with the tool inclined to the blank axis at an angle larger than the helix angle at the pitch radius of the blank, and rotating the tool in engagement with the blank, while simultaneously effecting a relative helical motion between the tool and blank about and in the direction of the blank axis, and while simultaneously effecting a further relative motion between the tool and blank about an axis which is perpendicular to the general direction of the engaged tooth surfaces in time with said helical motion and which is offset from the tool axis in a direction approximately radial of the blank.

10. The method of producing helical side tooth surfaces of convex profile shape on a gear which comprises engaging a disc type rotary tool, which has opposite side working surfaces that are of concave curved axial profile but less curved than the profiles of the tooth surfaces which are to be produced, with a gear blank with the tool inclined to the blank axis at an angle larger than the helix angle at the pitch radius of the blank, and rotating the tool in engagement with the blank, while simultaneously effecting a relative helical motion between the tool and blank about and in the direction of the blank axis, and while simultaneously effecting a further relative motion between the tool and blank about an axis parallel to but offset from the tool axis and in time with said helical motion.

11. In a machine for grinding helical gear teeth, a rotatable tool support, a rotary disc-shaped grinding wheel having a curved axial profile secured to said tool support to rotate coaxially therewith, a rotary work support, a pivoted carrier on which said tool support is mounted, said carrier being oscillatable about an axis parallel to the axis of said tool support and displaced from the axis of said tool support in a direction approximately radial of the axis of said work support, means for adjusting said tool support on said carrier to offset the axis of said grinding wheel from the axis of said carrier in said direction, means for turning said carrier on its axis in time with rotation of said work support, and means for effecting a further relative motion between the tool support and work support in the direction of the axis of the work support and in time with the rotation of the work support.

12. In a machine for grinding helical gear teeth, a rotatable tool support, a rotary disc-shaped grinding wheel, having a curved axial profile, secured to said tool support coaxially thereof to rotate therewith, a rotary work support, means for effecting a relative helical motion between the tool and work support, about and in the direction of the axis of the work support in repetitive strokes, a pivoted carrier on which said tool support is mounted, said carrier being oscillatable about an axis parallel to the axis of said tool support, means for adjusting said tool support in said carrier to offset the axis of the grinding wheel from the axis of said carrier in a direction approximately radial of said work support, means for rotating said tool support, and means for oscillating said carrier on its axis in time with said strokes so that one complete oscillation corresponds to one complete stroke and the ends of said oscillation occur

cur at about equal distances from the middle of said stroke.

13. In a machine for grinding helical gear teeth, a rotatable tool support, a rotary disc-shaped grinding wheel, having a curved axial profile, secured to said tool support coaxially thereof to rotate therewith, a rotary work support, means for effecting a relative helical motion between the tool and work supports about and in the direction of the axis of the work support in repetitive strokes, a pivoted carrier on which said tool support is mounted, said carrier being oscillatable about an axis parallel to the axis of said tool support, means for adjusting said tool support in said carrier to offset the axis of said grinding wheel from the axis of said carrier, means for rotating said tool support, means for oscillating said carrier in time with said strokes so that a complete oscillation of said carrier occurs for each said stroke and the ends of said oscillation occur at about equal distances from the middle of said stroke, and means for withdrawing said grinding wheel from working position at the end of each said stroke and for advancing the grinding wheel into working position again prior to each working stroke.

14. In a machine for grinding helical teeth, a rotatable tool support, a rotary disc-shaped grinding wheel, having a curved axial profile, secured to said tool support coaxially thereof to rotate therewith, a rotary work support, means for effecting a relative helical motion between the tool and work supports about and in the direction of the axis of the work support in repetitive strokes, a pivoted carrier on which said tool support is mounted, said carrier being oscillatable about an axis parallel to the axis of said tool support, means for adjusting said tool support in said carrier to offset the axis of said grinding wheel from the axis of said carrier, a head in which said carrier is mounted, means for rotating said tool support, a shaft journaled in said head, means for rotating said shaft once for each stroke cycle, and means actuated by said shaft for moving said tool support in opposite directions at opposite ends, respectively, of said strokes to move the grinding wheel, respectively, into and out of operative position, and means actuated by said shaft for oscillating said carrier in time and approximately in proportion with said strokes so that a complete oscillation of said carrier occurs for each stroke.

15. In a machine for grinding helical teeth, a rotatable tool support, a rotary disc-shaped grinding wheel secured to said tool support coaxially thereof to rotate therewith, a rotary work support, means for effecting a relative helical motion between the tool and work supports about and in the direction of the axis of the work support in repetitive strokes, a head adjustable about an axis perpendicular to the axis of the tool support, a carrier mounted in said head for oscillation about an axis parallel to the axis of said tool support, means for adjustably supporting said tool support on said carrier for adjustment thereon to offset the axis of the tool support from the axis of said carrier, means for rotating said tool support, a shaft journaled in said head, means for driving said shaft at the rate of one full turn for each stroke cycle, a cam secured to said shaft and operatively connected to said carrier to oscillate said carrier, and a second cam secured to said shaft and operatively connected to said carrier to move said grinding wheel into and out of grinding position in time with said strokes.

16. A machine for producing helical side tooth surfaces on a workpiece, comprising a rotary tool support, a rotary disc-shaped tool secured to said tool support coaxially thereof to rotate therewith, a rotary work support, means for adjusting the tool support angularly to incline a mean plane perpendicular to the axis of the tool to the axis of the work support, means for rotating the tool support, means for rotating the work support, means for effecting a relative feed movement between the tool support and the work support in the direction

of the axis of the work support and in time with the rotation of the work support, and means for effecting a continuous relative movement without reversal between the tool and work supports in said mean plane in time with said feed movement.

17. A machine for producing helical side tooth surfaces on a workpiece, comprising a rotary tool support, a rotary disc-shaped tool secured to said tool support coaxially thereof to rotate therewith, a rotary work support, means for adjusting the tool support angularly to incline a mean plane perpendicular to the axis of the tool to the axis of the work support, means for rotating the tool support, means for rotating the work support, means for effecting a relative feed movement between the tool support and the work support in the direction of the axis of the work support and in time with the rotation of the work support, and means for effecting relative movement between the tool and work supports in said mean plane in time with said feed movement and approximately longitudinally of the engaged tooth sides, and in which the center of the tool travels in a path concave toward the work.

18. A machine for producing helical side tooth surfaces on a workpiece, comprising a rotary tool support, a rotary disc-shaped tool secured to said support coaxially thereof to rotate therewith, a rotary work support, means for adjusting the tool support angularly relative to the work support to incline a plane perpendicular to the tool axis to the axis of the work support, means for rotating the tool support, means for rotating the work support, means for effecting a relative feed movement between the tool support and the work support in the direction of the axis of the work support and in time with the rotation of the work support, and means for effecting relative movement between the tool and work supports in time with said feed movement and approximately in proportion to said feed movement and about an axis parallel to but offset from the axis of said tool support in a direction approximately radial of the axis of the work support.

19. A machine for producing helical side tooth surfaces on a workpiece, comprising a rotary tool support, a rotary disc-shaped tool secured to said support coaxially thereof to rotate therewith, a rotary work support, means for adjusting the tool support angularly relative to the work support to incline a plane perpendicular to the tool axis to the axis of the work support, means for rotating the tool support, means for rotating the work support, means for effecting a relative feed movement between the tool support and the work support in the direction of the axis of the work support and in time with the rotation of the work support, means for effecting relative movement longitudinally of the helical side tooth surfaces between the tool and work supports in time with said feed movement and about an axis parallel to but offset from the axis of said tool support, and means for effecting further relative movement between the tool and work supports in a direction perpendicular to said parallel, offset axis at opposite ends of said feed movement to move the tool in and out of engagement with the work, respectively.

20. In a machine for producing tooth surfaces on a cylindrical workpiece, a rotatable tool support, a rotary disc-shaped tool secured to said tool support to rotate coaxially therewith, a rotatable work support, a pivoted carrier on which said tool support is mounted, said carrier being oscillatable about an axis parallel to the axis of said tool support, means for effecting a relative feed motion between said carrier and said work support in the direction of the axis of the work support, and means for turning said carrier on its axis in time with said feed motion and approximately in proportion thereto.

21. The method of producing essentially helical tooth surfaces on a rotatable cylindrical work piece which comprises engaging a disc-type rotary tool with a work

piece so that the axis of said tool is angularly disposed to the axis of said work piece, in rotating said tool in engagement with the work piece while turning the work piece on its axis and while effecting a relative feed motion between the tool and the work piece across the face of the work piece, said feed motion comprising a translation whose mean direction is inclined to the axis of the work piece, while the tool axis is maintained at a constant angle to the axis of the workpiece.

22. The method of producing essentially helical tooth surfaces on a rotatable cylindrical work piece, which comprises engaging a disc-type rotary tool with a work piece so that the axis of said tool is angularly disposed to the axis of the work piece, rotating said tool in engagement with the work piece while turning the work piece on its axis and while effecting a relative feed motion between the tool and the work piece across the face of the work piece, said feed motion being a translation in a plane inclined to the axis of the work piece, while the tool axis is maintained in a constant angular position, the relative path described in said plane being curved to produce a different tooth thickness at the ends than at the middle of the teeth.

23. In a machine for producing tooth surfaces on a cylindrical workpiece, a rotatable tool support, a rotary disk-shaped tool secured to said tool support to rotate coaxially therewith, a rotatable work support, a pivoted carrier on which said tool support is mounted, said carrier being oscillatable about an axis parallel to the axis of said tool support, means for effecting relative feed motion between said carrier and said work support in the direction of the axis of the work support, and means for turning said carrier on its axis in time with said feed motion to move said tool in an arc extending approximately in the longitudinal direction of the tooth surfaces engaged by said tool.

24. In a machine for producing tooth surfaces on a cylindrical workpiece, a rotatable tool support, a rotary disc-shaped tool secured to said tool support to rotate coaxially therewith, a rotatable work support, a pivoted

5

carrier on which said tool support is mounted, the pivot axis of said carrier and the axis of said tool support being arranged in parallelism, adjustment means for changing the distance between said two axes, means for effecting a relative feed motion between said carrier and said work support in the direction of the axis of the work support, means for turning said carrier on its pivot axis in time with said feed motion in one direction only during the operative feed motion in one direction, and means for changing the ratio of said turning motion to said feed motion.

20

25. The method of producing tooth surfaces on a cylindrical workpiece, which comprises providing a disk-type rotary tool having working portions disposed in a surface of revolution of concave axial profile and of convex profile in peripheral direction, rotating said tool on its axis in engagement with a cylindrical workpiece, effecting a relative feed motion between said tool and work piece in the direction of the axis of said work piece, effecting a distinct additional motion between said tool and workpiece by which the tool axis is moved relative to the workpiece in an arc in an average direction lengthwise of the tooth sides engaged by said tool while maintaining the tool axis and the axis of the workpiece each in a fixed direction, said additional motion being in one direction only during the operative part of the feed motion in one direction, and repeating said motions on other teeth of said workpiece.
